UNITED STATES PATENT OFFICE

145,955

DESIGN FOR A NUTCRACKER

Rudolf Rohm, Chicago, Ill.

Application December 29, 1945, Serial No. 125,161

Term of patent 7 years

(Cl. D44—29)

To all whom it may concern:

Be it known that I, Rudolf Rohm, a citizen of Germany, having resided in the United States more than eight years last past, and now residing at Chicago, in the county of Cook and State of Illinois, have invented a new, original, and ornamental Design for a Nutcracker, of which the following is a specification, reference being had to the accompanying drawing, forming a part thereof.

In the drawing:

Fig. 1 is a side elevational view of a nutcracker showing my new design.

Fig. 2 is an edge elevational view of the nutcracker shown in Fig. 1.

Fig. 3 is an end elevational view of the nutcracker shown in Fig. 1.

I claim:

The ornamental design for a nutcracker, as shown.

RUDOLF ROHM.
